UNITED STATES PATENT OFFICE.

FRANK CARTLIDGE, OF CINCINNATI, OHIO, ASSIGNOR TO SULLIVAN MACHINERY COMPANY, A CORPORATION OF MASSACHUSETTS.

MINING MACHINE.

Original application filed June 5, 1916, Serial No. 101,687. Divided and this application filed June 26, 1924. Serial No. 723,379.

To all whom it may concern:

Be it known that I, FRANK CARTLIDGE, a citizen of the United States, residing at Cincinnati, in the county of Hamilton and State of Ohio, have invented certain new and useful Improvements in Mining Machines, of which the following is a full, clear, and exact specification.

My invention relates to mining machines. It is an object of my invention to provide an improved mining machine having improved feeding mechanism whereby great flexibility in handling the machine may be obtained and whereby the machine may be moved at a plurality of speeds in different directions or made to move with a straight or turning movement as desired, it being a further object of my invention to obtain this flexible feeding from a single source of power which also drives a cutting or other operating mechanism of the machine. Other objects and advantages of my invention will hereinafter more fully appear.

This application is a division of my co-pending application, Serial No. 101,687, filed June 5, 1916.

In the accompanying drawings I have shown for purposes of illustration one embodiment which my invention may assume in practice.

In these drawings,—

Fig. 1 is a plan view, partly in section, of a mining machine embodying the illustrative form of my invention.

Fig. 2 is a side elevation of such a mining machine with some parts in section.

Fig. 3 is a section approximately on the line 3—3 of Fig. 1 with certain parts broken away to a different section line.

Fig. 4 is a plan view showing the gear connections for the feeding mechanism.

Fig. 5 is an enlarged section through the paying out member or take-up drum shown at the right of Figs. 1, 3 and 4 and is taken on the line 5—5 of Fig. 4.

Fig. 6 is an elevation, with parts broken away, of the winding drum or feed operating member shown at the right in Figs. 1 and 3, showing mechanism whereby this drum may be thrown into and out of action, the drum being in operative position in this figure.

Fig. 7 is a similar view showing the drum in its disconnected position.

Figs. 8, 9 and 10 are diagrammatic views showing the machine in different phases of operation. The proportions of parts may obviously vary and uniformity of dimension has not been adhered to rigidly in all the views.

In the form shown herein for purposes of illustration my improved mining machine has a main frame 15 conveniently provided with a flat bottom for sliding on the mine bottom and also provided with a projecting arm or bar 16 which carries in guides the cutter chain 17 provided with cutters 18 in the usual manner. This cutter chain is driven by a driving sprocket 19 mounted on a vertical shaft in the opposite end of the frame 15 from which the bar 16 projects. Fixed on the same shaft is a gear 20 whose upper face is cup-shaped for economy of space and this gear 20 meshes with a pinion 21 on the lower end of a vertical shaft 22 on whose upper end is fixed a bevel gear 23 meshing with a bevel driving pinion 24 on the shaft of the operating motor 25 which is most conveniently an electric motor. The upper and lower ends of the shaft 22 are supported respectively in bearings beyond the gears 21 and 23.

A worm 26 is fixed on the shaft 22 between the gears 21 and 23 and meshes with the worm wheel 27 and a horizontal shaft 28 from which the feeding mechanism is driven. The shaft 28 carries a pair of driving pinions 29 which mesh with a pair of gears 30 mounted on sleeves 31 and 32 respectively, which sleeves are coaxial with 90 and rotatable relative to a horizontal shaft 33, the sleeves 31 fitting directly on a bushing on the shaft 33. The two gears 30 are spaced apart but are connected to rotate together by bolts 34 upon each of which are mounted two planet gears 35 and 36 of slightly different size but rigid with each other so as to rotate together. The gears 35 are shown as slightly larger than the gears 36. The planet gears 35 mesh with a sun gear 37 and the planet gears 36 with a sun gear 38, the sun gear 38 being larger than the sun gear 37 to correspond to the difference in size of the planet gears 35 and 36. By reason of having the pinions 29 and gears 30 duplicated, all tendency to twist in the planet gears 35 and 36 and the sun gears 37 and 38 may be successfully re-

sisted. The sun gear 38 is fast on the shaft 33. The sun gear 37 forms part of a sleeve 39 rotatably mounted on the shaft 33 and located between such shaft and the sleeve 32. A sliding sleeve 40 has slideable toothed engagement with the sleeve 39 and is slideable in either direction along such sleeve by a finger 41 which may be operated by a shift lever 42. The sleeve 40 is provided with clutch teeth at both ends so that when slid in one direction from the neutral position in which it is free from any locking engagement, the teeth 43 on one end engage teeth 44 on the sleeve 32 to lock together the sleeves 32 and 39 and thus cause the sun and planet mechanism to rotate as a unit; and when slid in the other direction from neutral position teeth 45 on the other end of the sleeve 40 engage teeth 46 on a brake wheel 47 loosely mounted on the shaft 43 and cooperating with a brake band 48 which may be set or released by an operating handle 49 to hold stationary or permit any desired slipping of the brake wheel 47. The shaft 33 constitutes a driving member both for a feed operating member or drum 50 and a cooperating controlling member, take-up member, or paying out drum 51 shown respectively at the left and right hand sides of Figs. 1 and 3. For driving the member 50 the shaft 33 is provided at its left hand end, looking forward, with a driving pinion 52 which meshes with an internal gear 53 on such member in one position of the latter. The feed operating member or winding drum 50 is mounted on an eccentric bushing 54 which is in turn mounted on a stub shaft 55 around which it is adjustable by an operating handle 56 to shift the gear 53 into and out of mesh with the pinion 52. From Figs. 6 and 7 it will be noted that the operating handle may assume different predetermined positions for the connected and disconnected position of the drum 50.

For driving the paying out drum or take-up member 51, the shaft 33 has keyed on its right hand end, looking forward, a sleeve 57 which at its inner end is provided with gear teeth to provide a sun gear 58 and at its outer end forms a bearing surface for a rotatably mounted sleeve 59 which carries a plurality of planetary gears 60 which mesh with the sun gear 58 and with an internal gear 61 on the inside of such paying out drum or take-up member 51. The pins 62 on which the planet gears are mounted are carried at their right hand ends in the sleeve 59 and on their left hand ends carry a brake wheel 63 with which there cooperates a brake band 64 which may be set or released by an operating handle 65 to hold stationary or to permit any desired slipping of the brake wheel 63. The sleeve 59 has an outer annular portion 66 between which and the main portion of the sleeve is an annular space into which projects an annular sleeve member 67 carried by and constituting the bearing portion of the paying out drum 51, the member 67 being journaled on the sleeve 59 so that it supports the paying out drum. The outer surface of the annular member 67 and the inner surface of the annular portion 66 are toothed to engage with alternate ones of a series of clutch discs 68 which are located between the parts 66 and 67. The outer end of the sleeve 59 is threaded and has mounted thereon a clutch setting nut 69 provided with an operating ring 70 by which it may be rotated to engage with greater or less pressure the web by which the paying out drum 51 is mounted on the annular member 67 so as to cause more or less firm interengagement of the clutch discs 68. It should be noted that the teeth of the internal gear 61 are of such length and the parts of such construction that a certain degree of movement of the drum 51 longitudinally of the shaft 33 is permitted.

At this point it should be noted that the drum 51 is smaller than the drum 50, but by reason of the reduction occasioned by the driving of the drum 50 through the pinion 52 and internal gear 53 the drum 51, when the operating ring 70 is moved to effect the locking of the parts as later explained so that the drum 51 rotates at the same angular rate as the shaft 33, will have a greater peripheral speed than the peripheral speed of the drum 50. On the other hand, when the drum 51 is driven at the reduced rate which is accomplished by driving the internal gear 61 through the planet gears 60 and sun gear 58 the peripheral speed of the drum 51 will be less than that of the drum 50 and, moreover, the drum 51 will rotate in the opposite direction to drum 50.

The feed operating member or winding drum 50 and the take-up member or paying out drum 51 are herein shown as adapted to cooperate with a chain comprising portions 74 and 75 and an intermediate bight 76 having sufficient slack to permit the necessary independence of action of the drums 50 and 51. The chain may be carried through a suitable guide block 77 and over pulleys or sheaves 78, 79, 80 and 81 or some of them at the far corners of the frame 15, and over a pulley 82 between the pulleys or sheaves 78 and 79. These various pulleys or sheaves, or such of them as desired, may have swinging or swivel mounting. By means of these various pulleys or sheaves the chain may be carried from the drums or members 50 and 51 in different directions for getting different directions of movement.

In order to keep the parts properly lubricated, and free from the dust which always

exists in a mine, the gearing connecting the motor 25 to the shaft 33 is enclosed in a dust-proof, oil-tight casing 84 which completely encloses such gearing. The under side of this casing beneath the gears 30, 35 and 36 projects into the hollow upper shaft of the gear 20. The casing 84 is kept partly filled with oil which overflows along and lubricates the shaft 22. The gears 20 and 21, the sprocket 19 and parts of the cutter chain are partially enclosed by the frame 15 which is open at the end however, so that the arms 16 and the rest of the cutter chain may project therefrom. The gearing connecting the shaft 33 and the paying out drum 51 is substantially enclosed by the web carrying such drum and by the brake wheel 63 as clear from Fig. 5.

In operation the motor 25 drives the cutter chain 17 continuously through the driving connection already set forth as long as the motor is supplied with current. The motor 25 also drives the gears 30 continuously through the bevel pinion 24, bevel gear 23, worm 26, worm wheel 27, shaft 28 and pinions 29, and the rotation of the gears 30 causes the planet gears 35 and 36 to travel around the axis of the shaft 33. If the parts are in the position shown in Fig. 3, this travel of the planet gears 35 and 36 is without effect on the shaft 33 and produces no movement of either the winding drum 50 or the paying out drum 51 because the gear 37, which may be called the main reaction gear, is free to rotate and so there can be no reaction against it to cause movement of the shaft 33, which is subjected to the resistance offered to the feeding of the machine by either of the drums 50 or 51.

If a quick feeding is desired as for moving the machine from place to place or feeding it, the shift lever 42 is moved to cause intermeshing of the teeth 43 and 44, thereby locking together the sleeves 32 and 39 and causing the sun and planet mechanism connecting the pinions 29 and the shaft 33 to rotate as a unit and such shaft 33 to rotate at the same speed as the gears 30. The actual feeding at a rapid rate may now be obtained either from the drum 50 or the drum 51, but the more rapid feeding can be obtained from the drum 51 since notwithstanding its smaller diameter the reduction in the speed of rotation of the drum 50 due to the gearing 52, 53 causes the peripheral speed of the drum 50 to be less than that which occurs in the case of the drum 51 when the nut 69 is tightened so as to clamp together the clutch discs 68 (the brake band 64 being released) with the result that the drum 51 rotates at the same angular speed as the shaft 33. Under these circumstances both drums rotate in the same direction as the shaft 33 and as the chain portions are similarly rotated by the drums 50 and 51, by causing operation of the driving motor in the proper direction either portion may be wound in at a relatively fast speed, although, as pointed out, the highest speed can be obtained from the use of the drum 51. It may be noted that there are really three predetermined machine moving high speeds possible, the highest obtainable with the drum 51 rotating in the same direction and at the same angular speed of rotation as the shaft 33, an intermediate high speed with the motor rotating in the same direction and with the drum 50 the active drum, and the lowest high speed (which is yet considerably faster than the fastest of the slow speeds which will be subsequently mentioned) can be obtained by reversing the motor, releasing the friction discs 68 and clamping the member 63 with the brake band 64. This last speed may be varied from zero to its predetermined relatively high value by permitting the member 63 to slip by varying the tension upon the brake member 64. It will also be understood that the value of the highest high speed can be varied by allowing the discs 68 to slip relative to each other, this feed being entirely discontinued when the discs are allowed to slip freely.

If a slow feeding is desired, the shift lever 42 is thrown to cause intermeshing of the teeth 45 and 46. Then the travel of the planet gears 35 and 36 tends to produce movement of the sun gears 37 and 38 in opposite directions. The sun gear 38 tends to drive the shaft 33 and the sun gear 37 which is the main reaction gear tends to drive the brake wheel 47. The rotation and speed of the shaft 33 may now be controlled by the setting of the brake band 48 by its operating handle 49, the maximum slow speed of the shaft 33 being obtained when the brake band 48 holds the brake wheel 47 stationary. The direction of rotation of the shaft 33 at this slow speed is the same as it was at the high speed and slow feeding speeds may be obtained from either drum 50 or drum 51, there being possible three predetermined slow speeds all under frictional control by means of the brake band 48 and the fastest and slowest predetermined slow speeds being also under further frictional control by means respectively of the friction clutch 66 and brake band 64. It should be understood that if desired for any particular operation either of the portions 74 or 75 may be wound in the opposite direction to that shown upon its drums.

No extended discussion of the practical operation of the mechanism seems necessary, but one feature of the working operation may be briefly reviewed. The fact that there is a bight 76 in the chain between the members 50 and 51 has been noted and the effect of various movements of the machine

upon this bight is seen in Figs. 8, 9 and 10. In the first of these views there is shown diagrammatically a machine with its bar perpendicular to the face and the bight 76 between the feed operating and take-up members is clearly shown. In Fig. 9 the machine is shown with the cutter bar in advance of the rear end of the machine by quite a substantial amount, a somewhat extreme case being shown for demonstration purposes. Here it will be noted that more chain has been taken in by the feed operating member 50 than has been paid out by the take-up member 51 so that the amount of chain in the bight has been increased, thereby increasing the length of the portion of the chain between the points at which the chain leaves the machine frame at its opposite ends. Of course it will be understood that a corresponding position of the machine relative to the working face may be secured in various other ways, for example, by releasing the drum 50 by means of the handle 56, reversing the motor, pulling the rear end of the machine around by the drum 51 and the portion 75 of the chain, after which the motor might again be run in its original direction, the operator throwing the handle 56 to cause the drum 50 to become active and so that the machine will move ahead as previously described. It may be noted, moreover, that by reason of the fact that the member 51 tends to pay out the portion 75 more slowly than the portion 74 is wound in by the member 50, a position corresponding to that shown in Fig. 13 would be reached automatically unless the friction band 64 were allowed to slip. Fig. 10 shows a position of the machine in which the rear end of the machine has been allowed to get ahead of the cutter bar, this being accomplished, for example, by slackening up on the brake band 64 so that the portion 75 of the chain is paid out more rapidly than the portion 74 is wound in. In this operation of the parts it will be noted that the slack bight has been substantially diminished and that there is less chain between the points at which the feed operating member leaves the machine at its opposite ends than in either of the other two positions.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a mining machine, a frame, a projecting cutter carried thereby, a winding

drum, a paying-out drum, and a tension member extending in a slack bight between the two drums and extending from the winding drum forward from the frame near the end toward the cutter and from the paying-out drum backward from the frame at a point farther from the cutter end, and means for operating said two drums so that the paying-out operation is slower than the winding operation. 75

2. In a mining machine, a frame, a projecting cutter carried thereby, a winding drum, a paying-out drum, and a tension member extending in a slack bight between the two drums and extending from the winding drum forward from the frame near the end toward the cutter and from the paying-out drum backward from the frame at a point farther from the cutter end. 80

3. In a mining machine, a frame, a projecting cutter carried thereby, a winding drum, a paying-out drum, a tension member extending in a slack bight between the two drums and extending from the winding drum forward from the frame near the end toward the cutter and from the paying-out drum backward from the frame at a point farther from the cutter end, and means for operating said two drums at different speeds. 90

4. In a mining machine, a frame, a projecting cutter carried thereby, a winding drum, a paying-out drum, a tension member extending in a slack bight between the two drums and extending from the winding drum forward from the frame near the end toward the cutter and from the paying-out drum backward from the frame at a point farther from the cutter end, and means for varying the relation in the speeds of said two drums to vary the slackness of said bight. 100

5. In a mining machine, a frame bodily slideable laterally relative to the mine bottom, a projecting cutter carried thereby, a tension member extending forward from said frame at a point near the end toward the cutter and backward from the frame at a point farther from the cutter end and having a portion between said two points, a feed operating member engaging said last named portion, and winding means cooperating directly with said tension member for controlling the length of said portion. 110

6. In a mining machine, a frame slideable laterally on the mine bottom, a projecting cutter carried thereby, mechanism for feeding said frame laterally including a tension member extending in opposite directions from points adjacent the opposite ends of said frame and a feed operating member engaging a portion of said tension member between said points, and winding means cooperating directly with said tension member for controlling the length of said last. 120

mentioned portion during the cutting operation.

7. In a mining machine, a frame bodily slideable laterally relative to the mine bottom, a projecting cutter rigidly carried thereby, a tension member having a portion extending forward from said frame at a point near the end toward the cutter and a portion extending backward from the frame at a point farther from the cutter and also having a portion between said two points, a feed operating member engaging said last named portion, and winding means cooperating directly with said tension member for controlling the length of said last mentioned portion and the length of one of said oppositely extending portions.

8. In a mining machine, a frame slideable laterally relative to the mine bottom, a projecting cutter carried thereby, a tension member having a portion extending forward from said frame at a point near the end toward the cutter and a portion extending backward from the frame at a point farther from the cutter and also having a portion between said two points, and means including a feed operating member and a take-up member each engaging said last named portion for controlling the length of the last mentioned portion and the lengths of said oppositely extending portions.

9. In a mining machine, a frame slideable bodily laterally relative to the mine bottom, a projecting cutter carried thereby, a feed operating member carried thereby, a tension member cooperating with said operating member and extending forward from said frame at a point near the end toward the cutter and backward from the frame at a point farther from the cutter end and also having a portion between said two points, said feed operating member engaging said last named portion, and winding means cooperating directly with said tension member for controlling the length of said portion.

10. In a mining machine, a frame slideable laterally on the mine bottom, a projecting cutter rigidly connected thereto and carried thereby, a feed operating member carried thereby, a tension member cooperating with said operating member and extending forward from said frame at a point adjacent the cutter end thereof and backward from the frame at a point farther from the cutter end thereof and also having a portion between said two points, a feed operating member engaging said last named portion, and winding means cooperating directly with said tension member for controlling the length of said portion during the cutting operation.

11. In a mining machine, a unitary self-propelled mining machine slideable on the mine bottom, and including a frame, a pro-

jecting cutter bar thereon, a feed operating member thereon, and a tension member cooperating with said operating member and extending forward from said frame at a point adjacent one end thereof and backward from said frame at a point adjacent the other end thereof and also having a portion between said two points, said feed operating member engaging said last named portion, and winding means cooperating directly with said tension member for controlling the length of said portion during the cutting operation.

12. In a mining machine, a frame bodily slideable laterally relative to a mine bottom, a projecting cutter carried thereby, a feed operating member carried thereby, a tension member cooperating with said operating member and having a portion extending forward from said frame at a point near the end toward the cutter and a portion extending backward from the frame at a point farther from the cutter end and also having a portion between said two points, said feed operating member engaging said last named portion, and winding means between said operating member and said backwardly extending portion cooperating directly with said tension member for controlling the length of said last mentioned portion.

13. In a mining machine, a frame slideable bodily relative to the mine bottom, a projecting cutter carried thereby, a feed operating member carried thereby, a tension member cooperating with said operating member and extending forward and rearward from said frame at points adjacent the opposite ends thereof and having a portion between said points, said feed operating member engaging said last named portion, and a movable cooperating winding member cooperating directly with said tension member and adjustable to control the length of said portion.

14. In a mining machine, a frame slideable on the mine bottom, a projecting cutter carried thereby, and mechanism for feeding said frame laterally comprising a feed operating member carried thereby, a tension member cooperating with said operating member and extending forward from said frame at a point near one end thereof and backward from the frame at a point near the other end thereof and also having a portion between said two points, and a cooperating member movable about a horizontal axis and engaging said portion at a point between one of said points and the feed operating member.

15. In a mining machine, a frame slideable on the mine bottom, a projecting cutter carried thereby, and mechanism for feeding said frame laterally comprising a feed operating member carried thereby, a tension member cooperating with said operating

- member, and extending forward from said frame at a point near the end toward the cutter and backward from the frame at a point adjacent the opposite end thereof and also having a portion between said two points, and a cooperating member movable about a horizontal axis and engaging said portion at a point between said feed operating member and said second mentioned point.
16. In a mining machine, a frame slidable on the mine bottom, a projecting cutter rigidly connected thereto and carried thereby, a feed operating member carried thereby and rotatable on a transverse axis, a tension member cooperating with said operating member and extending forward from said frame at a point near the end toward the cutter and backward from the frame at a point adjacent the opposite end thereof and also having a portion between said two points, and a member cooperating directly with said tension member and rotatable about a transversely extending axis which lies in a line passing within the circumference of said feed operating member and controlling the length of said last mentioned portion.
17. In a mining machine, a frame, a projecting cutter carried thereby, a winding drum, a paying out drum, a tension member extending between said two drums and extending from the winding drum forward from the frame near the end toward the cutter and from the paying-out drum backward from the frame at a point farther from the cutter, and means for driving said two drums so that the paying out operation is slower than the winding operation.
18. In a mining machine, a frame, a projecting cutter carried thereby, a winding drum, a paying-out drum, a tension member extending between said two drums and extending from the winding drum forward from the frame near the end toward the cutter and from the paying-out drum backward from the frame at a point farther from the cutter, and means cooperating directly with said drums so that the paying-out operation is slower than the winding operation.
19. In a mining machine, a frame, a projecting cutter bar carried thereby, a winding drum, a paying-out drum, a flexible member providing flexible feeding portions extending from the winding drum forward from the frame near the end toward the cutter and from the paying-out drum backward from the frame at a point farther from the cutter end, and means for rotating said drums by power so that the paying-out operation is slower than the winding operation.
20. In a mining machine, a machine frame, a projecting cutter carried thereby, a winding drum, a paying-out drum, and a tension member extending from the winding drum forwardly from the frame near the end toward the cutter and from the paying-out drum backward from the frame at a point farther from the cutter end and comprising a portion between said drums, the coaction between said drums and said first and second mentioned portions preventing a transmission to the third mentioned portion of the tension under which either of the first mentioned portions is placed.
21. In a mining machine, a frame, a projecting cutter carried thereby, a winding drum, a paying-out drum, a tension member having a portion extending between the two drums and also having portions extending from the winding drum forwardly from the frame near the end toward the cutter and from the paying-out drum backward from the frame at a point farther from the cutter end, and means for operating said two drums at different speeds.
22. In a mining machine, a frame, a projecting cutter carried thereby, a winding drum, a paying-out drum, a tension member including a portion lying between the two drums and portions extending respectively from the winding drum forward from the frame near the end toward the cutter and from the paying-out drum backward from the frame at a point farther from the cutter, and means for varying the relation between the speeds of the two drums to vary the length of the portion between said drums.
23. In a mining machine, a frame bodily slidable laterally relative to the mine bottom, a projecting cutter carried thereby, a feed operating member on said frame rotatable by power and operative to cooperate with a flexible feeding portion to move the machine toward the remote end of said feeding portion, a flexible feeding portion cooperating therewith and extending to a point in advance of the machine, a rotatable element on said frame adapted to cooperate with a flexible feeding portion to retard the movement of said frame away from the remote end of such portion, a flexible feeding portion cooperating with said element and extending to a point in the rear of said frame as regards its direction of movement, a flexible portion connecting said first and second mentioned flexible feeding portions and constituting therewith a continuous flexible feeding member, and means cooperating with said rotatable element to brake the rotation thereof.
24. In a mining machine, a frame bodily slidable laterally relative to the mine bottom, a projecting cutter carried thereby, a feed operating member on said frame rotatable by power and operative to cooperate with a flexible feeding portion to move the machine toward the remote end of said feeding portion, a flexible feeding portion

- cooperating therewith and extending to a point in advance of the machine, a rotatable element on said frame adapted to cooperate with a flexible feeding portion to retard the movement of said frame away from the remote end of such portion, a flexible feeding portion cooperating with said element and extending to a point in the rear of said frame as regards its direction of movement, 10 a flexible portion connecting said first and second mentioned flexible feeding portions and constituting therewith a continuous flexible feeding member, and means cooperating directly with said rotatable element to effect rotation thereof by power.
25. In a mining machine, a frame bodily slidable laterally relative to the mine bottom, a projecting cutter carried thereby, a feed operating member on said frame rotatable by power and operative to cooperate with a flexible feeding portion to move the machine toward the remote end of said feeding portion, a flexible feeding portion cooperating therewith and extending to a point in advance of the machine, a rotatable element on said frame adapted to cooperate with a flexible feeding portion to retard the movement of said frame away from the remote end of such portion, a flexible feeding portion cooperating with said element and extending to a point in the rear of said frame as regards its direction of movement, a flexible portion connecting said first and second mentioned flexible feeding portions and constituting therewith a continuous flexible feeding member, and means cooperating with said rotatable element to selectively brake the rotation thereof or effect the rotation thereof by power.
40. 26. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two operator-controlled flexible portion engaging elements and they rotating on axes fixed relative to said frame.
27. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two operator-controlled flexible portion engaging elements and they rotating on axes fixed relative to said frame and means for rotating one of the same by power.
55. 28. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two flexible portion engaging winding elements and they each rotating on an axis fixed relative to said frame, and means for rotating

- slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two flexible portion engaging winding elements rotating on axes fixed relative to said frame and means for rotating both of the same by power.
29. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, means controlling the length of said portion including but two flexible portion engaging winding elements and they rotating on axes fixed relative to said frame, and means for rotating the same by power in the same or opposite directions.
30. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two flexible portion engaging winding elements each rotating on an axis fixed relative to said frame, and means for rotating the same by power in opposite directions at unequal speeds.
31. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, and means controlling the length of said portion including but two flexible portion engaging winding elements and they rotating on axes fixed relative to said frame, and means for rotating the same in the same direction at equal speeds.
32. In a mining machine, a frame bodily slidable laterally relative to the mine bottom, a projecting cutter carried thereby, a tension member extending forward from said frame at a point near the end toward the cutter and backward at a point farther from the cutter and having a portion between said two points, means controlling the length of said portion including but two flexible portion engaging winding elements and they each rotating on an axis fixed relative to said frame, and means for rotating

- the same at unequal predetermined speeds in the same direction, said means including means for effecting rotation of the element rotating at the faster predetermined speed
- 5 at substantially the same speed as the slower predetermined speed.
33. The combination, in a mining machine, with cutting mechanism, of feeding mechanism therefor comprising a driving motor, a shaft, a plural-speed connection between said motor and said shaft whereby the latter may be driven at a plurality of predetermined speeds by the former, two feed operating members operatively connectible with said shaft, means for connecting one of said feed operating members to said shaft for driving thereby at a plurality of predetermined speeds while rotation of said shaft remains constant, and a continuous flexible feeding member cooperating with both of said feed operating members at points between its ends.
34. In a mining machine, the combination with cutting mechanism, of feeding mechanism therefor comprising a driving motor, a shaft, a plural-speed connection between said motor and said shaft whereby the latter may be driven at a plurality of predetermined speeds by the former, two feed operating members operatively connectible with said shaft, means for connecting one of said feed operating members to said shaft for driving thereby at a predetermined speed in one direction and at a different predetermined speed in the opposite direction while rotation of said shaft remains constant, and a continuous flexible feeding member cooperating with both of said feed operating members at points between its ends.
35. The combination in a mining machine of cutting mechanism and feeding mechanism therefor comprising a driving motor for both mechanisms, a shaft, a plural-speed connection between said motor and said shaft whereby the latter may be driven at a plurality of predetermined speeds by the former, two feed operating members operatively connectible with said shaft, means for connecting one of said feed operating members to said shaft for driving thereby at a predetermined speed in one direction and at a different predetermined speed in the opposite direction while rotation of said shaft remains constant, the angular rate of one of said predetermined speeds being equal to the angular rate of rotation of said shaft, and a continuous flexible feeding member cooperating with both of said feed operating members at points between its ends.
36. The combination, in a mining machine, of cutting mechanism and feeding mechanism therefor comprising a driving motor for both of said mechanisms, a shaft, a plural-speed connection between said
- motor and said shaft whereby the latter may be driven by the former, two feed operating members operatively connectible with said shaft, means for connecting one of said feed operating members to said shaft for driving thereby at a predetermined speed in one direction and at a different predetermined speed in the opposite direction while rotation of said shaft remains constant, said means for connecting said feed operating member to said shaft including friction mechanism controllable to vary the rotation of said shaft from said predetermined speeds, and a continuous flexible feeding member cooperating with both of said feed operating members at points between its ends.
37. The combination with a mining machine, of feeding mechanism therefor comprising a driving motor, a shaft, a plural predetermined speed driving connection between said motor and said shaft whereby the latter may be driven at a plurality of predetermined speeds by the former, two feed operating members operatively connectible with said shaft, means for selectively connecting said feed operating members in driven relation to said shaft operative to wholly disconnect the same from the latter, and a continuous flexible feeding member operatively engaging each of said feed operating members at points between its ends.
38. In a mining machine, feeding mechanism comprising a driving motor, a shaft, a plural predetermined speed connection between said motor and said shaft whereby the latter may be driven at a plurality of predetermined speeds by the former, said connection including friction mechanism adjustable to variably diminish the speed of said shaft from one of said predetermined speeds, two feed operating members operatively connectible with said shaft, and means for selectively connecting said feed operating members in driven relation to said shaft operative to wholly disconnect the same from the latter, and a continuous flexible feeding member operatively engaging each of said feed operating members at points between its ends.
39. In a mining machine, a frame having a forwardly projecting cutter bar, a motor on said frame, a feed operating member rotatable on a transverse axis at one side of said frame, a flexible feeding member co-operating therewith and adapted to be anchored at its opposite ends at opposite sides of said machine frame during cutting across a face, operative connections between said feed operating member and said motor including intermeshing elements respectively coaxial with said feed operating member and fixed as to relative rotary movement with respect thereto and constituting a

- driving member for said last mentioned element, and means for interrupting said drive including means for bodily moving the axis of rotation of one of said elements.
40. In a mining machine, a frame having a forwardly projecting cutter bar, a motor on said frame, a feed operating member rotatable on a transverse axis at one side of said frame, a flexible feeding member cooperating therewith and adapted to be anchored at its opposite ends at opposite sides of said machine frame during cutting across a face, operative connections between said feed operating member and said motor including intermeshing elements respectively coaxial with said feed operating member and fixed as to relative rotary movement with respect thereto and constituting a driving member for said last mentioned element, and means for interrupting said drive including means for bodily arcuately moving the axis of rotation of one of said elements.
41. In a mining machine, a frame having a forwardly projecting cutter bar, a motor on said frame, a feed operating member rotatable on a transverse axis at one side of said frame, a flexible feeding member cooperating therewith and adapted to be anchored at its opposite ends at opposite sides of said machine frame during cutting across a face, operative connections between said feed operating member and said motor including intermeshing elements respectively coaxial with said feed operating member and fixed as to relative rotary movement with respect thereto and constituting a driving member for said last mentioned element, and means for interrupting said driving connections including a rotatably mounted eccentric supporting said feed operating member and rotatable to bring said first mentioned element into mesh with said second mentioned element and to move it out of mesh.
42. In a mining machine, a frame, cutting mechanism thereon and feeding mechanism thereon including a flexible feeding member normally extending laterally in opposite directions from opposite ends of said frame and a laterally extending feed operating member, and guiding means for said flexible member for directing said frame transversely during cutting including a laterally extending guiding member disposed adjacent said feed operating member.
43. In a mining machine, a frame, cutting mechanism fixed thereon, feeding mechanism for said frame including a flexible feeding member normally extending laterally in opposite directions from opposite ends of said frame, a laterally extending feed operating member, and guiding means for said flexible member including a pair of guiding members disposed adjacent to said feed operating member and at opposite sides of a cutting mechanism and flexible feeding
- plane including the axis of rotation of the latter.
44. In a mining machine, a frame slideable on its bottom on a mine bottom, cutting mechanism thereon including a rigidly connected longitudinally extending cutter bar, and feeding mechanism thereon for feeding said frame bodily laterally including a flexible feeding member, a feed operating member rotating on a transverse axis and projecting laterally from one side of said frame, and guiding means for said flexible feeding member adjacent said feed operating member and also at the opposite ends of said frame.
45. In a mining machine, a frame slideable on a mine bottom, cutting mechanism thereon including a rigidly connected longitudinally extending cutter bar, and feeding mechanism thereon including a flexible feeding member extending laterally in opposite directions from the opposite ends of said frame, a feed operating member extending laterally from one side of said frame, and guiding means for said flexible member disposed adjacent said feed operating member and also at the opposite ends of the same side of said frame.
46. In a mining machine, a frame slideable on a mine bottom, cutting mechanism thereon including a rigidly connected longitudinally extending cutter bar, and feeding mechanism thereon including a flexible feeding member extending laterally in opposite directions from the opposite ends of said frame, a feed operating member extending laterally from one side of said frame, and guiding means for said flexible member including a pair of guiding members disposed adjacent said feed operating member and guiding members at the opposite ends of the same side of said frame.
47. In a mining mechanism, feeding mechanism including a plurality of feed driving elements, a single flexible feeding member engaging said elements, and means for using one of said elements as a feed operating member and the other as a take-up member.
48. In a mining machine, feeding mechanism including feed operating and take-up members rotatable on transverse axes, means cooperating directly therewith for effecting rotation thereof at different speeds, and a continuous flexible feeding member engaging both of the same.
49. In a mining machine, feeding mechanism including feed operating and take-up members rotatable on transverse axes, means cooperating directly therewith for effecting rotation thereof simultaneously at different speeds, and a continuous flexible feeding member engaging both of the same.
50. In a room and pillar mining machine,

- means including feed operating and take-up members rotatable on transverse axes and located at the opposite sides of the machine, means for driving said feed operating and 5 take-up members independently of each other, and a continuous flexible feeding member operatively connected to said feed operating and take-up members during transverse cutting.
- 10 51. In a room and pillar mining machine, cutting mechanism and flexible feeding means including feed operating and take-up members rotatable on transverse axes and located at the opposite sides of the machine, 15 means for driving said feed operating and take-up members cooperating directly therewith, and a continuous flexible feeding member operatively connected to said feed operating and take-up members during transverse cutting.
- 20 52. The combination with a room and pillar mining machine, of feeding mechanism thereon including feed operating and take-up members rotatable on transverse axes and located on the opposite sides thereof, a continuous flexible feeding element operatively connected to both of said members, and means for rotating said members simultaneously or either of the same at will.
- 25 53. In a mining machine, a machine frame, feeding mechanism thereon including feed operating and take-up members rotatable on transverse axes and located on the opposite sides of said frame, an idler located on a parallel axis adjacent each of said members, and a flexible feeding member engaging said members and said idlers.
- 30 54. In a mining machine, a machine frame, feeding mechanism thereon including feed operating and take-up members rotatable on transverse axes and located on the opposite sides of said frame, a continuous flexible feeding member engaging both of said members, guiding idlers therefor located on parallel axes adjacent one of said member, and cooperating guiding means for directing the opposite ends of said flexible member laterally from opposite ends of said frame.
- 35 55. In a mining machine, a frame slideable laterally on the mine bottom, a projecting cutter carried thereby, mechanism for feeding said frame laterally including a tension member extending in opposite directions from points adjacent the opposite ends of said frame and a feed operating member engaging a portion of said tension member between said points and winding means cooperating directly with said tension member for controlling the length of said last mentioned portion during the cutting operation.
- 40 56. In a mining machine, a frame having a forwardly projecting cutter bar and feeding mechanism including a single continuous flexible feeding member, a rotatable
- feed operating member adapted to cooperate directly with said flexible feeding member at a point between the ends of the latter and rotatable on a transverse axis at one side of said frame, a cooperating rotatable member rotating on a transverse axis at the opposite side of said frame and also cooperating directly with said flexible feeding member at a point between the ends of the latter, a motor on said frame, means for driving said first mentioned rotatable member from said motor, and means for driving said last mentioned rotatable member from said motor in opposite directions at different speeds.
- 45 57. A mining machine comprising a frame slideable on the mine bottom and a projecting cutter bar, and means for feeding said frame and guiding the same during cutting and at other times including a flexible feeding member providing a plurality of flexible feeding portions disposable during cutting transversely of a face in opposite directions from the opposite ends of said frame, and feed operating and controlling means including rotatable feed operating means cooperating with said flexible feeding member, and driving means for said rotatable feed operating means operable without reversal of said motor to cause winding in of one of said portions at a predetermined cutting speed and to cause the drawing in of the other flexible feeding portion at a higher predetermined cutting speed or at a still higher predetermined machine moving speed which exceeds the maximum potential cutting speed of said machine under normal working conditions.
- 50 58. In a mining machine, feeding mechanism including feed operating and take-up members rotatable on transverse axes, means for driving each of the same by power to effect rotation thereof, and a continuous flexible feeding member engaging both of said members.
- 55 59. In a mining machine, feeding mechanism including feed operating and take-up members rotatable on transverse stationary axes, and a continuous flexible feeding member engaging both of the same.
- 60 60. In a mining machine, feeding mechanism including frictionally controlled feed operating and take-up members rotatable on transverse axes, and a continuous flexible feeding member engaging both of the same.
- 65 61. In a mining machine, feeding mechanism including feed operating and take-up members rotatable on stationary transverse axes at different predetermined speeds, and a continuous flexible feeding member engaging both of the same.
- 70 62. The combination with a room and pillar mining machine, of feeding means including feed operating and take-up members rotatable thereon on transverse rela-

- tively fixed axes, a continuous flexible feeding member engaging said members, and means for varying the length of the portion thereof between said members.
5. 63. The combination with a room and pillar mining machine, of flexible feeding means thereon including feed operating and take-up members rotatable on transverse stationary axes and located on the opposite sides thereof, a continuous flexible feeding member, and means for operatively connecting the latter to said members to feed said machine laterally.
10. 64. The combination with a room and pillar mining machine, of flexible feeding means thereon including feed operating and take-up members rotatable on transverse axes and located on the opposite sides thereof, a continuous flexible feeding member operatively connected to said members, and means for actuating said members to feed said machine toward either end of said flexible member.
15. 65. The combination with a room and pillar mining machine, of feeding mechanism thereon including feed operating and take-up members rotatable on transverse axes and located on the opposite sides thereof, a continuous flexible element operatively connected to both of said members, and means for rotating either member.
20. 66. The combination with a room and pillar mining machine, of feeding mechanism thereon including feed operating and take-up members rotatable on transverse axes and located on the opposite sides thereof, a continuous flexible feeding element operatively connected to both of said members, and means for rotating either member at different speeds.
25. 67. The combination with a room and pillar mining machine, of feeding mechanism thereon including feed operating and take-up members rotatable on transverse stationary axes and located on the opposite sides thereof, a continuous flexible feeding element operatively connected to both of said members, and means for rotating said members simultaneously.
30. 68. The combination with a mining machine frame slidable on its bottom on a mine bottom, of a laterally extending feed operating member thereon, a continuous flexible feeding member cooperating with said feed operating member and extending around the same on one side of said frame and in opposite directions from the opposite ends of said frame, a laterally extending guiding means adjacent said feed operating member around which the slack side of said flexible feeding member is extended, and a cooperating laterally extending guiding member engaging the tight side of said flexible feeding member at a point in front of said feed operating member.
35. 69. In a mining machine, a frame, cutting mechanism thereon, feeding mechanism thereon including a flexible feeding member normally extending laterally in opposite directions from opposite ends of said frame and a laterally extending feed operating member, and guiding means for said flexible member for directing said frame transversely during cutting including a laterally extending guiding member rotatable on a pivot disposed above the bottom of said operating member.
40. 70. In a mining machine, a frame, cutting mechanism fixed thereon, feeding mechanism for said frame including a flexible feeding member normally extending laterally in opposite directions from opposite ends of said frame and a laterally extending feed operating member, and guiding means for said flexible member for directing said frame transversely during cutting including a laterally extending guiding member rotatable on a pivot disposed above the bottom of said operating member.
45. 71. In a mining machine, a frame slidable on its bottom on a mine bottom, cutting mechanism thereon including a rigidly connected longitudinally extending cutter bar, and feeding mechanism thereon for feeding said frame bodily laterally including a flexible feeding member, a feed operating member extending laterally from one side of said frame, and guiding means for said flexible feeding member adjacent said feed operating member and also at the opposite ends of said frame.
50. 72. The combination with a mining machine, of feeding mechanism therefor including a continuous flexible feeding member cooperating therewith and having single strands extending from the opposite sides of said machine, feed operating means operative to draw in either strand at a cutting speed, and adjustable means on said machine for limiting or interrupting the paying out of one of said strands while permitting drawing in of the other.
55. 73. In a mining machine, a frame slidable on a mine bottom, cutting mechanism thereon including a rigidly connected longitudinally extending cutter bar, and feeding mechanism thereon including a flexible feeding member extending laterally in opposite directions from the opposite ends of said frame, a feed operating member extending laterally from one side of said frame, and guiding means for said flexible member disposed adjacent said operating member and also at the opposite ends of the same side of said frame.
60. 74. In a mining machine, a frame, cutting mechanism thereon, feeding mechanism thereon including flexible feeding means and a laterally disposed feed operating member, cooperating guiding means for said flexible

- feeding means disposed upon a pivot above the bottom of said feed operating member, and cooperating guiding means for said flexible feeding means disposed at the opposite ends of one side of said frame. 50
75. In a mining machine, a frame, cutting mechanism thereon, feeding mechanism thereon including flexible feeding means and a laterally disposed feed operating member, cooperating guiding means for said flexible feeding means rotatable upon an axis disposed below the axis of said feed operating member, and cooperating guiding means for said flexible feeding means disposed at the opposite ends of one side of said frame. 55
76. In a mining machine, a frame, cutting mechanism thereon, feeding mechanism thereon including a single flexible feeding member and a rotatable laterally extending feed operating member, and guiding means for said flexible feeding member including guiding members disposed at opposite ends of said frame and a laterally extending guiding member rotatable upon an axis disposed above the bottom of said feed operating member. 60
77. In a mining machine, a frame slidable on the bottom, cutting mechanism thereon, feeding mechanism thereon including a single flexible feeding member and a rotatable laterally extending feed operating member, and guiding means for said flexible feeding member including guiding members disposed at opposite ends of said frame and a laterally extending guiding member rotatable upon an axis disposed below the axis of said feed operating member. 65
78. In a mining machine, a frame having a forwardly projecting cutter bar and feeding mechanism including a single continuous flexible feeding member, a rotatable feed operating member adapted to cooperate directly with said flexible feeding member at a point between the ends of the latter and rotatable on a transverse axis at one side of said frame, a cooperating rotatable member rotating on a transverse axis at the opposite side of said frame and also cooperating directly with said flexible feeding member at a point between the ends of the latter, a motor on said frame, means for driving said first mentioned rotatable member from said motor in opposite directions at different speeds, and means for driving said last mentioned rotatable member from said motor at different speeds. 70
79. The combination with a mining machine frame slidable on its bottom on a mine bottom, of a laterally extending feed operating member thereon, a continuous flexible feeding member cooperating with said feed operating member and extending around the same on one side of said frame and in opposite directions from the opposite ends of said frame, and a laterally extending guiding means adjacent said feed operating member around which the slack side of said flexible feeding member is extended. 75
80. The combination with a mining machine frame slidable on its bottom on a mine bottom, of a laterally extending feed operating member thereon, a continuous flexible feeding member cooperating with said feed operating member and extending around the same on one side of said frame and in opposite directions from the opposite ends of said frame, a laterally extending guiding means adjacent said feed operating member around which the slack side of said flexible feeding member is extended, and a cooperating laterally extending guiding member engaging the tight side of said flexible feeding member at a point in front of said feed operating member. 80
81. In a mining machine, a frame, cutting mechanism thereon, feeding mechanism thereon including a flexible feeding member normally extending laterally in opposite directions from opposite ends of said frame and a laterally extending feed operating member, and guiding means for said flexible member for directing said frame transversely during cutting including a laterally extending guiding member disposed adjacent said operating member. 85

In testimony whereof I affix my signature.

FRANK CARTLIDGE.

feeding means disposed upon a pivot above the bottom of said feed operating member, and cooperating guiding means for said flexible feeding means disposed at the opposite ends of one side of said frame.

75. In a mining machine, a frame, cutting mechanism thereon, feeding mechanism thereon including flexible feeding means and a laterally disposed feed operating member, cooperating guiding means for said flexible feeding means disposed below the axis of said feed operating member, and cooperating guiding means for said flexible feeding means disposed at the opposite ends of one side of said frame.

76. In a mining machine, a frame, cutting mechanism thereon, feeding mechanism thereon including a single flexible feeding member and a rotatable laterally extending feed operating member, and guiding means for said flexible feeding member including guiding members disposed at opposite ends of said frame and a laterally extending guiding member rotatable upon an axis disposed above the bottom of said feed operating member.

77. In a mining machine, a frame slidable on the bottom, cutting mechanism thereon, feeding mechanism thereon including a single flexible feeding member and a rotatable laterally extending feed operating member, and guiding means for said flexible feeding member including guiding members disposed at opposite ends of said frame and a laterally extending guiding member rotatable upon an axis disposed below the axis of said feed operating member.

78. In a mining machine, a frame having a forwardly projecting cutter bar and feeding mechanism including a single continuous flexible feeding member, a rotatable feed operating member adapted to cooperate directly with said flexible feeding member at a point between the ends of the latter and rotatable on a transverse axis at one side of said frame, a cooperating rotatable member rotating on a transverse axis at the opposite side of said frame and also cooperating

directly with said flexible feeding member at a point between the ends of the latter, a motor on said frame, means for driving said first mentioned rotatable member from said motor in opposite directions at different speeds, and means for driving said last mentioned rotatable member from said motor at different speeds.

79. The combination with a mining machine frame slidable on its bottom on a mine bottom, of a laterally extending feed operating member thereon, a continuous flexible feeding member cooperating with said feed operating member and extending around the same on one side of said frame and in opposite directions from the opposite ends of said frame, and a laterally extending guiding means adjacent said feed operating member around which the slack side of said flexible feeding member is extended.

80. The combination with a mining machine frame slidable on its bottom on a mine bottom, of a laterally extending feed operating member thereon, a continuous flexible feeding member cooperating with said feed operating member and extending around the same on one side of said frame and in opposite directions from the opposite ends of said frame, a laterally extending guiding means adjacent said feed operating member around which the slack side of said flexible feeding member is extended, and a cooperating laterally extending guiding member engaging the tight side of said flexible feeding member at a point in front of said feed operating member.

81. In a mining machine, a frame, cutting mechanism thereon, feeding mechanism thereon including a flexible feeding member normally extending laterally in opposite directions from opposite ends of said frame and a laterally extending feed operating member, and guiding means for said flexible member for directing said frame transversely during cutting including a laterally extending guiding member disposed adjacent said operating member.

In testimony whereof I affix my signature.

FRANK CARTLIDGE.

Certificate of Correction.

It is hereby certified that in Letters Patent No. 1,538,685, granted May 19, 1925, upon the application of Frank Cartlidge, of Cincinnati, Ohio, for an improvement in "Mining Machines," errors appear in the printed specification requiring correction as follows: Page 7, line 129, claim 32, strike out the word "each" and for the word "axis" read *axes*; page 11, line 88, claim 70, for the words "above the bottom" read *below the axis*; and that the said Letters Patent should be read with these corrections therein that the same may conform to the record of the case in the Patent Office.

Signed and sealed this 18th day of October, A. D. 1925.

[SEAL.]

KARL FENNING,
Acting Commissioner of Patents.
